MINE RAIL TIE AND ANCHOR

Sam Morano, Morgantown, W. Va.

Application October 27, 1938, Serial No. 237,359

2 Claims. (Cl. 238—356)

This invention relates to certain new and useful improvements in mine rail ties and rail anchors.

The primary object of the invention is to provide car track structures for mines and has particular reference to the tie construction and devices for anchoring rails thereon.

A further object of the invention is to provide a mine rail tie and rail anchor wherein each rail supported on the metallic tie has the base flange thereof at one side engaged by a clamp rigid with the tie with the other rail flange engaged by a pair of pivotally mounted clamps that are adapted to be locked in their rail-engaging position.

A further object of the invention is to provide a mine rail tie and rail anchor of the foregoing character with means carried by the tie adjacent each rail seat for forcing the rail into engagement with rigid clamps carried by the tie and aiding for the proper feeding of the rail to the base flange thereof in proximity of the tie seat to be bent or distorted and further to position the spaced flange of the rail for engagement by pivotally mounted clamps carried by the tie.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a side elevational view of a mine rail tie constructed in accordance with the present invention, a pair of rails fragmentarily illustrated and shown in section, being mounted on the tie,

Figure 2 is a top plan view of the tie with the rails removed and showing the rigid and pivotally mounted rail flange-engaging clamp,

Figure 3 is a fragmentary bottom plan view of the tie, showing the sliding plates at the under side of the tie for locking the pivoted rail flange engaging clamp in operative position,

Figure 4 is a fragmentary vertical longitudinal sectional view taken on line 4—4 of Figure 2, showing the pivotally mounted rail flange engaging clamp and the locking plate associated with the clamp,

Figure 5 is a vertical cross-sectional view taken on line 5—5 of Figure 1, showing the screw operated lever carried by a side of the tie for forcing a rail into position on its seat on the tie,

Figure 6 is a cross-sectional view taken on line 6—6 of Figure 2,

Figure 7 is a fragmentary vertical longitudinal sectional view, similar to Figure 4, showing another form of latch device for holding the pivoted rail flange engaging clamp in operative position, and

Figure 8 is a cross-sectional view similar to Figure 6, showing a modified construction for the support of the latch plate.

Referring more in detail to the accompanying drawings, the reference numeral 10 designates in general a metallic tie for mine rails, the tie being of inverted U-shaped construction, comprising a top wall 11 and side walls 12. The rails 13 supported on the top wall 11 of the tie are spaced at the proper mine gage with one of the rails positioned adjacent one end of the tie and in proximity of a side wall of the mine passage to give better access to the devices for anchoring the rails on the ties.

Each rail 13 comprises base flanges 14 and 15, the base flange 14 being engaged by a clamp 16 rigid with the top wall of the tie 10, the other flanges 15 of the rails being engaged by pivotally mounted clamps. A rod 17 extends transversely of the tie 19 beneath the top wall 11 thereof and projects through the side walls 12, the rod 17 carrying a head 18 on one end thereof engaged with the adjacent side wall 12 as shown in Figure 5, while the other threaded projecting end thereof receives a lock nut 19, the rod 17 being positioned laterally of the base flange 15 of the rails 13. A pair of clamps 20 is pivotally mounted upon the rod 17 and projects upwardly through the opening 21 in the top wall 11 of the tie, each clamp 20 carrying a clamping arm 22 adapted to be engaged with the base flange 15 of the rail 13 while a foot 23 projects laterally of the clamp 20, substantially in the plane of the clamping arm 22 and above the rod 17, the openings 21 in the top wall 11 of the tie being of a size to permit free movement therethrough of the foot 23 of the clamp 20.

A locking device is associated with the clamps 20 for holding the clamping arms 22 engaged with the base flanges of the rails and include a latch plate 24 slidably mounted longitudinally of the tie between the top wall 11 thereof and in engagement with the lower face of said top wall, the latch plate being supported upon the cross rod 25 extending between the side walls 12 of the tie. The end of the latch plate 24 adjacent the clamp 20 is adapted to underlie the foot 23 of the clamp to hold the clamp against piv-

otal movement with the clamping arms 22 there-
of engaged with the base flanges 15 of the rail,
the operating means for the sliding latch plate
24 for moving the same into and out of opera-
tive positions relative to the clamp foot 23 com-
prising an arm 26 struck out and upwardly there-
from at the end spaced from the clamp foot 23
with the arm projecting upwardly through the
opening 27 in the top wall 11 of the tie, the
10 upper end of the arm 26 carrying a depending
flange 28. A lock device for the latch plate 24
comprises a lever 29 pivotally mounted as at 30
upon the upper side of the top wall 11 of the
tie, one end of the lever 29 carrying a hook 31
15 adapted to be engaged beneath the flange 28 of
the arm 26 with an operating handle 32 at the
other end of the lever 29. With the lever 29 en-
gaged with the arm 26 and flange 28 of the latch
plate 24 as shown in Figure 4, the forward end
20 of the latch plate is disposed beneath the foot
23 of the clamp 20 for holding the clamping arm
22 in engagement with the base flange of the
rail. When the lever 29 is moved on its pivotal
mounting 30 to displace the hook 31 laterally
25 of the arm 26 and flange 28 of the latch plate,
the latter is permitted to slide upon the guide
supporting rod 25 to be disengaged from and
positioned laterally of the clamp foot 23 to per-
mit pivotal movement of the clamp 20.
30 In assembling the rails 13 on the tie 10, the base
flange 14 of the rail is first engaged with the rigid
clamp 16 and the clamps 29 that were moved to
the dotted line position as shown in Figure 4 are
then shifted to the full line positions illustrated
35 and locked in position by the latch plate 24.
Should difficulty be encountered in seating the
rails on the tie, due to distortion or bent portions
of the rail flanges, means is provided for forcing
the rail into proper seating position on the tie 10
40 and as shown in Figures 1 to 3 include such a de-
vice for each rail seat having an arm 33 pivotally
supported at the lower end thereof as at 34 upon
the outer side of a side wall 12 of the tie adjacent
its lower end, the upper end of the arm 33 having
45 a lever 35 pivotally mounted thereon as at 36, a
nose 37 carried by one end of the lever 35 being
disposed for engagement with the rail 13, while
the other end of the lever 35 has a screw bolt 38
threaded therethrough that has the lower end
50 thereof engaged with the top wall 11 of the tie.
Upon downward movement of the screw 38
through the lever 35, the nose 37 of the lever is
forced into engagement with the rail 13 for mov-
ing the same onto its seat on the tie and into posi-
tion to be engaged by the rigid clamps 16.
55 A webbing arrangement 39 depends from the
underside of the top wall in which earth may be
packed to aid in holding the tie in position.
A modified form of locking lever for the latch
60 plate 24 is shown in Figure 7, the handle 32a of
the latch plate 24a having a rod 40 depending
downwardly therethrough with an angular hand
grip 41 upon its upper end, the rod 40, carrying
65 a disk 42 adjacent its lower end with a coil spring
43 surrounding the rod between the handle 32a
and disk 42 for normally forcing the rod 40 in a
downward direction, the lower end of the rod 40
below the disk 42 being receivable in a depression
44 formed in the upper wall 11 of the tie for hold-

ing the lever 29a in its locked position relative
to the sliding latch plate 24.

In lieu of the cross rods 25 for the support of
the sliding latch plate 24, the modified construc-
tion shown in Figure 8 may be provided and in
which the top wall 11a with a longitudinally ex-
tending groove 25a in the inner face of each side
wall 12a adjacent the bottom face of the top wall
11a and into which groove 25a the side edges of the
latch plate 24a are slidably mounted for guiding
movements therein.

From the above detailed description of the in-
vention, it is believed that the construction and
operation thereof will at once be apparent and
while there are herein shown and described the
15 preferred embodiment of the invention, it is
nevertheless to be understood that minor changes
may be made therein without departing from the
spirit and scope of the invention as claimed.

I claim:

1. In a mine rail tie and rail anchor, a metallic
tie having a flat top wall and depending side walls
with a rigid rail clamp for a rail supported on the
top wall, a cooperating rail clamp for the rigid
rail clamp hingedly mounted below the top wall
25 of the tie and extending through an opening
therein and having a foot extending above the
tie, means for locking the hinged rail clamp in
rail engaging position, the locking means includ-
ing a plate longitudinally slidable beneath and
30 in contact with the bottom face of the top wall of
the tie into and out of operative engagement with
the hingedly mounted rail clamp beneath the foot
thereof and to be protected by the top wall of the
tie, guide and supporting means for the slidable
35 plate, an arm carried by the slidable locking plate
and extending above the tie through an opening
in the top wall thereof, a lever pivotally connected
to the upper side of the tie and engageable with
said arm for holding the locking plate in operative
40 position and a tensioned pin carried by the lever
and interlockingly engaged with the tie for holding
the lever in its plate locking position.

2. In a mine rail tie and rail anchor, a metallic
tie having a top wall and depending side walls, a
rigid rail clamp for a rail supported on the top
wall, a cooperating rail clamp for the rigid rail
clamp hingedly mounted below the top wall of the
tie and extending through an opening therein and
having a foot extending above the tie, means for
locking the hinged rail clamp in rail engaging
45 position including a longitudinally slidable plate
mounted in the tie beneath the top wall thereof
and in sliding contact with the bottom face of the
top wall, the inner faces of the side walls of the
tie having guide grooves therein for guiding and
sliding reception of opposite side edges of the
50 slidable plate, said plate being longitudinally
movable of the tie into and out of operative en-
gagement with the hingedly mounted clamp be-
neath the foot thereof, the top wall of the tie
having a slotted opening therein, an arm carried
55 by the slidable locking plate extending upwardly
through said opening, and a lever pivotally con-
nected to the top wall of the tie and engageable
with said arm for holding the locking plate in
operative position.

SAM MORANO.
